United States Patent [19]

Nakao et al.

[11] Patent Number: Des. 327,078

[45] Date of Patent: ** Jun. 16, 1992

[54] **INSTRUMENT FOR TRANSFERRING BOATS FOR THERMAL TREATMENT OF SEMICONDUCTOR WAFERS**

[75] Inventors: Ken Nakao, Sagamihara; Seishiro Sato, Machida; Wataru Ohkase, Sagamihara, all of Japan

[73] Assignee: Tel Sagami Limited, Kanagawa, Japan

[**] Term: 14 Years

[21] Appl. No.: 301,994

[22] Filed: Jan. 25, 1989

[57] CLAIM

The ornamental design for an instrument for transferring boats for thermal treatment of semiconductor wafers, as shown.

DESCRIPTION

FIG. 1 is a front elevational view of an instrument for transferring boats for thermal treatment of semiconductor wafers showing our new design;

FIG. 2 is an elevational view, the remainder of the cylindrical member being the same throughout in appearance;

FIG. 3 is a top plan view;

FIG. 4 is a bottom plan view;

FIG. 5 is an elevational view thereof;

FIG. 6 is a top perspective view; and,

FIG. 7 is a bottom perspective view thereof.
